UNITED STATES PATENT OFFICE.

JACOB B. KNUDSEN, OF CHICAGO, ILLINOIS, ASSIGNOR OF ONE-HALF TO FRANCIS H. QUAIL, OF CHICAGO, ILLINOIS.

VALVE.

1,326,938.

Specification of Letters Patent.

Patented Jan. 6, 1920.

Application filed January 19, 1916. Serial No. 73,005.

To all whom it may concern:

Be it known that I, JACOB B. KNUDSEN, a citizen of the United States, residing at Chicago, in the county of Cook and State 5 of Illinois, have invented new and useful Improvements in Valves, of which the following is a full, clear, concise, and exact description, reference being had to the accompanying drawing, forming a part of this 10 specification.

My invention relates to valves, and more particularly to valves for use in the confinement of gas under pressure.

It is one of the objects of my invention 15 to provide a packless valve in which the danger of leakage, either through the bonnet or the outlet, is removed.

I have described in the following specification and illustrated in the accompanying 20 drawings embodiments of my invention, it being understood that changes may be made in the form, construction and arrangement of the parts without departing from the spirit of my invention or exceeding the scope of 25 the appended claims, the forms herein disclosed being merely preferred embodiments thereof.

In the drawing—

Figure 1 is a vertical cross sectional view 30 of a valve constructed in accordance with my invention;

Fig. 2 is an enlarged cross sectional view 35 of a portion of Fig. 1, the section being taken on the line 2—2 of Fig. 1, looking in the direction of the arrows; and

Fig. 3 is a view similar to Fig. 1 showing a modified form of the valve member there shown.

Referring to the drawing, 5 represents the 40 receptacle in which the gas or other fluid is confined and which has an enlarged portion 6 through which is a central threaded opening to receive the threaded arm 7 of the valve casing 8. The latter is a casting substantially in the form of a Greek cross, the four arms of which may be designated, for convenience, as the inlet, outlet, safety outlet and bonnet arms. Through the inlet arm 7 is a passage 9 which has communication 45 with the interior of the receptacle 5 by means of a plurality of ports 10 formed in a washer-like member 11 which is in screw threaded connection with the arm 7 and has an out-turned flange 12 bearing against the end of 50 the latter member.

In communication with the passage 9 are the discharge port and a safety port. Opening into the passage 9 and forming, in effect, a continuation thereof, and of a cross section substantially smaller than the same, 60 is a passage 13 through the casing member and opening into a central chamber 14 into which also opens a passage 15 communicating with the discharge port 16. This port and passage are in the outlet arm 17 65 of the valve casing 8, this arm being substantially at right angles with the inlet arm 7. The end of the outlet arm 17 is screw threaded for engagement with a receiving tank or the like. 70

Diametrically opposite the outlet arm 17 is the safety outlet arm 18, screw threaded at the end to receive a cap 19 in which is a safety outlet communicating with a passage 20, which in turn communicates with 75 a passage 21 opening into the main passage 9, the outlet being closed by a thin strip of copper 22 or other suitable substance designed to blow out in case the pressure in the receptacle becomes in excess of a predetermined amount. 80

Slidably embraced by the washer-like member is a valve stem 23 which has an enlarged portion 24 and a flange 25 on which is a washer 26 of fiber, rubber or other 85 suitable material. This flange and its washer constitute the valve proper which engages a shoulder 27 formed in the valve casing at the point where the restricted passage 13 and the main passage 9 meet, said 90 shoulder forming in effect the valve seat. Beyond the washer 26 the valve stem has a frusto-conical portion 28 which is at its base of a cross section substantially equal to that of the passage 13, so that when the valve is 95 displaced away from its seat the opening for the passage of the gas will gradually increase in extent. At the end of the valve stem beyond the frusto-conical portion is a cylindrical head 29 which fits snugly but 100 slidably into the passage 13 and which is provided in its side with a plurality of grooves 30 (in this instance, four) running from end to end, whereby the flow of gas when the valve is opened is more or less 105 restricted inasmuch as the gas can pass into the central chamber 14 only via these grooves. The valve is normally held closed against its seat by a coiled spring 31 which bears against the flange 25 of the valve 110

stem and against the washer-like member 11, and by the pressure of the confined gas. It is opened by means now to be described.

- The bonnet arm of the casing member 8, which is the arm diametrically opposite the inlet arm 7, is formed with a chamber in its outer end and from the bottom of this chamber to the central chamber 14 is a threaded bore, in which operates a threaded stem 32. 5 The latter, as will be seen by the drawing, extends into the central chamber 14, and it is formed with a pointed end 33 which is received by a depression in the end of the valve stem head 29. At the other end, this 10 threaded stem 32 extends beyond the end of the casing arm and terminates in a squared end 34. The latter is engaged by a squared socket formed in the end of an intermediate operating and guide member 35 embraced 15 within the bonnet 36 which is suitably threaded to be screwed over the threaded end of the casing arm as clearly appears in Fig. 1. The member 35 has a downward extension in the form of a sleeve 35^a which surrounds the threaded stem and provides a 20 further guide for the same. The end of this sleeve enters and rotates in a suitable groove formed in the bottom of the casing arm chamber. To provide proper joints the bonnet 36 has a shoulder bearing against the end 25 of the casing arm, the shoulder being provided with an annular groove to receive a corresponding annular ridge on the end of the casing arm.
- 30 The intermediate operating member 35 has a central shank extending outward through an opening in the head 37 of the bonnet and terminating in a squared end 38 which is engaged by a squared socket in the end of an operating member 39. The latter is 35 rotatably embraced within a cap 40 which is in threaded connection with the end of the bonnet 36. The cap 40 has an inwardly abutting shoulder engaging a flange 41 on the 40 inner end of the operating member 39 whereby the latter is held down against the bonnet head 37. The end of the cap 40 is open and an annular space provides access to the squared end 42 of the operating member 39 45 whereby the latter may be turned by means of a suitable wrench or other instrument.
- 50 In the intermediate member 35 a shoulder is formed by reason of the shank, and the face of the shoulder is provided with a plurality of concentrically arranged teeth 43. Interposed between this shoulder and the head 37 of the bonnet is a washer 44, which is preferably of a metal softer than the metal comprising the engaging member so 55 that when the shoulder bears against the washer the teeth 44 are forced into the softer metal and form in effect a plurality of ground joints. The member 35 is held firmly 60 against the washer 43 and thereby clamps up against the bonnet head by means 65 of the same against the bonnet head by means

of a coiled spring 45 which surrounds sleeve 35^a in the chamber of the casing arm, and which bears against the bottom thereof and against a washer 46 engaging the member 35. This spring will maintain a tight joint, thus 70 effectually preventing leakage in the bonnet.

When the operating member 39 is rotated by a wrench the motion is transmitted to the member 35 and thence to the threaded stem 32 as will be apparent. The latter member 75 will have also an endwise movement, the squared end 34 thereof sliding in its guide formed by the socket in the member 35 and the sleeve 35^a. This movement of the threaded stem is transmitted to the valve stem by 80 reason of their abutting ends, thus forcing the valve member, against the pressure of the spring and the confined gas, away from its seat and so permitting the gas to flow to the discharge port. This flow however 85 will not be sudden and unrestricted, for, owing to the frusto-conical shape of the valve stem, the opening at first is very slight and only gradually widens as the stem is given further displacement. Even when the 90 valve is wide open the gas is still restricted in its flow by reason of the fact that its path is through the grooves 30 in the head 29.

The valve is closed by turning the operating member 39 in the opposite direction, this 95 motion being transmitted to the connecting member and thence to the threaded stem, thus withdrawing the latter which permits the valve member to return to seating position under the force of the spring 31, or that 100 together with the pressure of the gas, in case any remains.

In Fig. 3 I have disclosed a modification of my invention which has a ground valve member instead of the flange seating member above described. The enlarged portion 105 24 of the valve stem 23 has a flange 50 with a downturned edge 51, the coiled spring 31 bearing against this flange. Beyond the latter the valve stem is frusto-conical in shape, the base being of a cross section substantially greater than that of the passage 110 13, so that as the spring 31 and the gas pressure force the valve against the edge of the shoulder, the ground conical surface effectually closes the passage. In other respects 115 this form of the invention is like the form just described.

The construction of the bonnet and its associated parts is such as to prevent leakage 120 in the bonnet when gas is flowing. Furthermore, leakage from the receptacle is prevented effectively because of the valve construction, and the fact that it is opened against the pressure and held shut in a manner such that the pressure aids rather than opposes, instead of being mechanically held closed against the pressure. And it will be noted that the greater the pressure the more firmly the valve is held against its seat. As 125 13

a result of such a construction there is no strain on the threads of the stem 33 so that the latter will not work loose, and the consequent necessity of frequently tightening the operating member is removed. Also there are no parts or joints to become loose by the jarring and rough handling which the receptacle is likely to undergo in transportation and the like. So it will be seen 10 that by my invention I have provided a packless, non-leaking valve, a valve in which the operating member is mounted on the bonnet independent of the valve stem, and one in which sudden and unrestricted flow 15 of the fluid confined is prevented.

Having thus described my invention what I claim as new and desire to secure by Letters Patent is:—

1. In a pressure tank valve the combination with a valve casing of a removable bonnet therefor, a valve seating with the pressure mounted in said casing, a threaded stem bearing at its lower end on the valve stem and having an irregular shaped upper end, 20 a rotatable member in the bonnet having a shoulder at its upper end seating on an interior shoulder on the bonnet and provided with an irregular shaped extension projecting through the bonnet, said member having 25 an irregular socket for the reception of the irregular end on the threaded stem and a rotatable vertically stationary operating member mounted on the bonnet and having an irregular socket for the irregular shaped end 30 of said rotating member.
  2. In a pressure tank valve, the combination with a valve casing of a removable bonnet therefor, a valve seating with the pressure, a stem threaded in said valve casing 40 and having an irregular shaped upper end, a rotatable member in the bonnet having a shoulder at its upper end seating on an interior shoulder on the bonnet and provided with an irregular shaped extension projecting 45 through the top of the bonnet, said member having an irregular socket for the reception of the end of the threaded stem, a coiled spring for holding the shoulder on
- said rotating member seated, a rotatable, vertically stationary operating member 50 mounted on the bonnet and having an irregular socket for the irregular-shaped extension of the rotating member, the valve stem and threaded stem being structurally disconnected but operatively connected. 55
3. In a pressure tank valve, the combination with a valve casing having an enlarged recess in its lower end communicating with an exit passage, a valve member mounted in said enlarged recess and having a frusto- 60 conical portion extending into the exit passage, a shoulder on said valve, a closure plug for said recess having apertures for the passage of the tank contents, a downwardly extending stem projecting through said plug 65 and guiding said valve member, a coiled spring interposed between the shoulder on said valve and said plug for holding the valve in position, an upwardly projecting extension on said valve member, a threaded 70 stem mounted in said casing having its lower end bearing upon said extension and having an irregular shaped upper end, a bonnet for said casing, a rotatable member in said bonnet having a shoulder at its upper end 75 seating against an interior shoulder in said bonnet and provided with an irregular shaped socket for the reception of the irregular shaped end of the threaded stem, a coiled spring holding the shoulder on said 80 rotatable member in seated position, said rotatable member having an irregular shaped projection extending through the bonnet and a vertically stationary rotatable operating member mounted on said bonnet and having 85 an irregular shaped socket for the reception of said irregular shaped projection on the rotatable member.

In witness whereof, I have hereunto subscribed my name in the presence of two witnesses. 90

JACOB B. KNUDSEN.
